ATTORNEY

UNITED STATES PATENT OFFICE.

CYNTHIA PETTIGREW, OF PLANTERSVILLE, MISSISSIPPI.

MAIL-CATCHER.

1,300,005.

Specification of Letters Patent.

Patented Apr. 8, 1919.

Application filed September 30, 1918. Serial No. 256,271.

To all whom it may concern:

Be it known that I, CYNTHIA PETTIGREW, a citizen of the United States, residing at Plantersville, in the county of Lee and State 5 of Mississippi, have invented certain new and useful Improvements in Mail-Catchers, of which the following is a specification.

This invention relates to a mail bag receiving apparatus and has for its object the 10 production of a simple and efficient means for automatically closing the receiving apparatus as soon as a mail bag has been delivered thereto.

Another object of this invention is the 15 production of a simple and efficient means for holding the mail bag receiving device in an open or receiving position, and at the same time permitting the same to be automatically released as soon as a mail bag has 20 been thrown in engagement therewith.

With these and other objects in view, this invention consists of certain novel constructions, combinations, and arrangements of parts as will be hereinafter fully described 25 and claimed.

In the drawings:—

Figure 1 is a perspective view of the mail bag receiving apparatus; and,

Fig. 2 is a transverse section therethrough 30 looking down from the top of the device.

By referring to the drawings it will be seen that 1 designates a standard which supports a top plate 2 near the upper end thereof and this top plate 2 may be made of any 35 suitable or desired material such as metal and is provided with suitable projecting ears 3. A pintle pin 4 is journaled upon the ears 3 as shown in Fig. 1 and this pin extends through a sleeve 5 of the mail bag 40 receiving member. This mail bag receiving member comprises a plurality of projecting substantially curved fingers 6 arranged in spaced relation upon the sleeve 5 as shown clearly in Fig. 1 of the drawing. The outer 45 ends of these fingers 6 are beveled as indicated at 7 for the purpose of permitting the outer ends of the fingers to firmly fit against the plate 2 when the fingers 6 are in a closed position, such as is shown in dotted lines in Fig. 2 of the drawing. A connecting bar 8 extends transversely across the fingers 6 as shown in Fig. 1 and this bar is adapted to assist in holding the outer ends of the fingers 6 in spaced relation. A 50 latching hook 9 which consists of a sleeve having spaced claws 10 is hingedly secured

upon the connecting or reinforcing bar 8 and these claws are adapted to engage the cross head 11 of the retaining bar 12, which gives the bar 12 a substantially T-shaped 60 construction at its outer end.

A retaining bar 12 above mentioned is pivotally secured to the rear face of the plate 2 by means of a pivot connection 13 shown in Fig. 2 and this bar extends laterally from the plate 2 and projects in the rear of the mail bag receiving apparatus.

The laterally extending fingers 11 are adapted to be engaged by the hooked ends 10 of the hook 9 and in this way the fingers or arms 6 will be held in an operative position ready to receive a mail bag.

The hook 9 is engaged by means of a suitable spring 14, this spring 14 being also secured to the front face of the plate 2 as indicated at 15 70

and it should be understood that as the mail bag strikes the front edge of the fingers 6, the same will be pushed rearwardly to a slight degree and this movement will cause 80

the hook 9 to disengage the laterally extending fingers 11 of the retaining or locking rod 12, the spring 14 holding the hook 9 out of engagement with the rod 12 as soon as the hook has been released from the laterally extending fingers 10 thereof. The 85

spring 14 will also cause the fingers or arms 6 to be thrown upon the plate 2 and in this way firmly hold a mail bag between the fingers 6 and the plate 2.

It should be understood that the releasing of the fingers 6 is 90

accomplished solely by the impact of the mail bag which is thrown against the front edge of the arms 6. This impact will automatically release the fingers and the spring 14 will then swing the arm to a closed position, thereby firmly carrying the mail bag toward the plate 2 and firmly holding the mail bag between the fingers 6 and the plate 2.

It of course should be understood that 100 any suitable number of fingers 6 may be employed and if it should be desired one or

more of these series of fingers such as illustrated in Fig. 1 may be employed without departing from the spirit of the invention, 105

as for instance three sets of fingers may be employed in order to receive a mail bag and in view of the fact that it would be merely a duplication of the parts to use a plurality of these fingers for receiving the 110 mail bag, it is thought unnecessary to illustrate and describe the same in detail.

It of course should be understood that certain detail mechanical changes may be made in the present invention without departing from the spirit thereof, so long as these changes fall within the scope of the appended claims.

What is claimed is:—

1. In a device of the class described, the combination of a supporting plate, a retaining bar carried by said plate and having a cross head at its outer end, a mail bag receiving member hingedly mounted upon one end of said plate, a latching hook supported by said receiving member, and resilient means for normally urging said hook in one direction, said hook being adapted to engage said cross head to hold the receiving member in a set position, although when the receiving member is swung slightly in one direction said resilient means will swing said hook from engagement with said cross head, thus allowing the receiving member to swing around into engagement with said supporting plate.
2. In a device of the class described, the combination of supporting means, a retaining bar carried by said means and having a cross head at its outer end, a mail bag receiving member pivoted on said plate, a latching hook pivotally mounted upon the

rod member and including a pair of claws, a spring connected to the said hooks and said plate, said claws fitting upon each side of said bar to engage said head and thus hold the receiving member in a set position, although when the receiving member is swung slightly in one direction said spring will move said claws into engagement with said cross head thus allowing the tension of the spring to swing said receiving member into engagement with said plate.

3. In a device of the class described, the combination of a supporting plate, a mail bag receiving member pivotally mounted upon said plate, a bar carried by said receiving member, a latching hook pivotally mounted upon said bar, a coil spring connected to said plate and said hook, and retaining means carried by said plate, said hook engaging said retaining means for holding said receiving member in a set position although when said receiving member is swung slightly in one direction said spring will move the hook from engagement with the retaining means and thus allow the spring to swing said receiving member into engagement with the said plate.

In testimony whereof I affix my signature.

CYNTHIA PETTIGREW.
